(57) **CLAIM**

I claim the ornamental design for a chair, as shown and described.

DESCRIPTION

FIG. 1 is an upper perspective view of a chair;

FIG. 2 is a front plan view of the design shown in FIG. 1;
FIG. 3 is a back plan view of the design shown in FIG. 1;
FIG. 4 is a right side plan view of the design shown in FIG. 1;

FIG. 5 is a left side plan view of the design shown in FIG. 1;

FIG. 6 is a top plan view of the design shown in FIG. 1; and,
FIG. 7 is a bottom plan view of the design shown in FIG. 1.
The broken lines in the figures are for the purpose of
illustrating portions of the chair, which form no part of the
claimed design. The shade lines shown represent surface
shading and not surface ornamentation, color, or material
type.

1 Claim, 7 Drawing Sheets
